(57) **CLAIM**

The ornamental design for a tattoo needle cluster, as shown and described.

DESCRIPTION

FIG. 1 is a top perspective view of a tattoo needle cluster, showing a first embodiment of my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a top perspective view of a tattoo needle cluster, showing a second embodiment of my new design.

FIG. 8 is a front elevational view thereof.

FIG. 9 is a rear elevational view thereof.

FIG. 10 is a left side elevational view thereof.

FIG. 11 is a right side elevational view thereof.

FIG. 12 is a top plan view thereof.

FIG. 13 is a top perspective view of a tattoo needle cluster, showing a third embodiment of my new design.

FIG. 14 is a front elevational view thereof.

FIG. 15 is a rear elevational view thereof.

FIG. 16 is a left side elevational view thereof.

FIG. 17 is a right side elevational view; and,

FIG. 18 is a top plan view thereof.

The broken lines showing the tattoo needle base solder or connection material are unclaimed subject matter and form no part of the claimed design.

Portions of the product that are not seen in the drawings are unclaimed subject matter and form no part of the claimed design.

1 Claim, 12 Drawing Sheets
